UNITED STATES PATENT OFFICE

2,302,929

STOVE AND FURNACE CONSTRUCTION

William F. Allen, Nashville, Tenn.

Application December 19, 1940, Serial No. 370,895

2 Claims. (Cl. 126—58)

The invention relates to stoves and furnaces generally, and has for an object to present an improved construction intended particularly for use in burning coal or other fuel adapted to be used in a similar way.

It is the cardinal object of the invention to present a stove of this character which will be especially efficient in combustion of all fuel elements of coal and other solid fuels, especially where there is a more or less volatile element in the fuel which is given off at temperatures below that of combustion, which in prior stoves tends to become lost and passes up the chimney.

Another important object of the invention is to present a stove of the hopper feed type which is adapted to contain or accommodate a very large supply of fuel in proportion to the bulk of fuel actually in course of combustion and to present novel means for insuring utilization of the more volatile elements by bringing them into contact with combustion supporting gases at the highest possible temperatures, thus insuring a high efficiency in combustion.

More specifically, it is an object of the invention to feed secondary air to the top of the fuel chamber after refueling, by means of novel construction of channels, for complete combustion of gases.

It is another important object of the invention to present a simple construction of hopper in which the parts may be assembled or replaced with a minimum of effort.

Additional objects, advantages and features of invention reside in the construction, arrangement and combination of parts, involved in the embodiment of the invention, as will be more readily understood from the following description and accompanying drawings, wherein:

Figure 1 is a front elevation of a stove constructed in accordance with my invention.

Figure 2 is an enlarged vertical section taken at right angles to Figure 1.

Figure 3 is a cross section on the line 3—3 of Figure 2.

Figure 4 is a cross section on the line 4—4 of Figure 2.

Figure 5 is a perspective view of the tile sections employed in the stove.

Figure 6 is a perspective view of the cast linings employed.

Figure 7 illustrates plan views of a pair of tile members as constructed for use in the stove.

Figure 8 is a plan view of one of the cast lining members.

Figure 9 is a perspective view thereof.

Figure 10 is a fragmentary sectional view illustrating the relationship of the tile and lining sections when installed in the stove.

Figure 11 is a side elevation of a modified form of stove, embodying a radiator.

Figure 12 is a top plan view thereof.

Figure 13 is a fragmentary enlarged vertical sectional view.

Figure 14 is a cross section on the line 14—14 of Figure 13.

Attention is first invited to Figures 1 and 2 of the drawings, wherein there is shown a stove 10 having a steel casing 11 of any suitable diameter and height, which will vary, of course, with the particular requirements, since the stove may be made in various sizes.

The casing 11 includes a base 12 and a top head 13, the latter having a swingable closure 14 permitting filling of the stove with fuel, as will be described. Any suitable number of legs 15 are secured to the base 12, and in the present instance, the legs are provided with right angular flange portions 16 adapted to lie flush beneath the base.

A grate rest support 17 is positioned within the casing 11 resting upon the base 12, as clearly shown in Figure 2.

The stove, in the present instance, has been shown as cylindrical, although this construction is not arbitrary, and the support 17, it will be noted, has upper and lower inturned flanges 18. At suitable points the lower flange 18 will have apertures aligned with apertures of the base and the flange 16 of respective legs for reception of bolts 19. Thus the legs, base and support are firmly secured together.

As shown in Figure 2, the support 17 is of a height to support a grate rest 20 above the base 12 forming an ash chamber 21, and in order that access may be had to the chamber, the support and casing are formed with aligned openings 22. A suitable door 23 including a damper 24 is swingably mounted to the casing, as at 25, for closing the openings.

The grate rest support 17 has formed at its upper edge a plurality of spaced openings 26, and since the grate rest 20 is laid flush upon the upper edge of the support 17, the rest 20 will also include openings 26' in registry with the openings 26. A suitable grate 27 cooperates with the rest for support of fuel, and shaking of ash from the fire pot.

The grate rest 20 has a circumscribing upstanding rib 28, spaced inwardly from the casing 11 which functions for support of vertically ar-

ranged tile members 29, the tile members having a thickness to snugly fit between the rib 28 and the casing 11.

For an understanding of the construction of the tile members 29, attention is now directed to Figure 5 of the drawings. It will be seen that the tile members are shaped to snugly abut the casing 11, the outer face of each tile having a longitudinal groove 30 extending the full length of the tile, and when the tile members are arranged within the casing, the groove of the tile members are to be aligned with the openings 26 and 26' as shown in Figure 2.

The tile members 29 each have a rabbeted portion 31 at their upper ends forming an upstanding rib 32 outwardly offset with respect to the inner face of the tile members. Each of the tile members 29 are identical in construction with the exception of four, indicated at 33 and 34, and these are arranged in pairs, preferably at diametrically opposite sides of the assembled tile members within the casing, as clearly shown in Figure 4. Each of the tile members 33 and 34 are formed with laterally extended recesses 35, terminating inwardly of the vertical edge of the tile, and each being positioned at the same height (see Fig. 2).

Between each pair of the members 33 and 34, a spacer strap 36 is interposed, of the same length as the tile members and of a width to snugly retain all of the tile members in their proper assembled relation. The spacers 36 are of slight thickness as compared to that of the tiles and are provided with spaced, right angular baffle plates 37, positioned throughout the length of the spacers 36 except at the point opposite the recesses 35, where they are omitted. The combined thickness of the spacer and baffles is less than one-half the thickness of the tile members and there is thus provided a pair of channels extending from the grate to the top of the tiles. It should be noted also that the tile members 33 and 34 are constructed as rights and lefts and when assembled with the spacer form a cross-shaped channel.

The structure thus far set forth describes the construction of the fire-box proper, and in order that gases may be drawn to the top of the fuel within the stove for ignition, it is necessary to provide a supply of secondary air as well as combustible gases to such area, and this is carried out in the provision of a second air chamber, generally indicated by the reference character 38, the construction of which will now be described.

As shown in Figures 2 and 6, the chamber is formed from a plurality of interlocked sections 39 spaced from the casing, and since these sections are of identical construction, a description of one will suffice, and attention is now invited particularly to Figures 8 and 9. The section 39 is formed as a casting, of arcuate formation so that when the several sections are interlocked within the shell, they will conform therewith. The upper edge of the section has an outwardly turned flange 40 of a width corresponding to the thickness of the rib 32 of the tile members, and the longitudinal edges of the section 39 are provided with offset ears 41 and 42 in alternate relation. Through the longitudinal center of the section there are arranged a pair of vertically disposed flanges 43 extending from the inner face of the section and at right angles thereto, the flanges being interrupted as at 44 adjacent the upper and lower edges of the section. Directly opposite each of the interruptions, respective

10 pockets 45 and 46 are formed, extending in opposite directions. These pockets have a depth in the direction of the outer face, the function of which will be explained hereinafter. Between the flanges 43 baffle plates 47 are provided, there being two in the present instance, one below each of the interruptions 44 of the flanges. The casting is formed with a plurality of secondary air openings 48 adjacent its upper edge immediately beneath the flange 40.

15 It will be apparent that by the provision of alternately disposed ears 41 and 42 the sections may be readily interlocked one with the other, and when so arranged the flanges 40 will firmly abut the casing 11, the lower edge of the sections will thus be in position to seat within the rib 32 of the tile sections, and the sections 39 will be maintained in firm spaced relation with respect to the casing.

The operation will be readily understood from the following description, it being assumed that a fire has been made upon the grate 27 as customary, after which the fuel is deposited through the filling door 14, and preferably the stove will accommodate 110 pounds of coal or other fuel.

Obviously with such a large amount of coal or other fuel in the stove, burning of the entire mass is not practical, and it is therefore necessary that the fire on the grate function solely as 20 a means for releasing combustible gases from the fuel, and these with the secondary air are ignited above the fuel line within the stove. When the fuel is first deposited in the stove there is a short period of coking of the fuel by reason 25 of the fire on the grate, the fuel emitting a white smoke which continues for a period of five or ten minutes more or less. The damper 24 being open, secondary air is drawn into the secondary chamber and discharged into the combustion 30 chamber where it mixes with the smoke and gases and then ignited. Upon ignition of the gases, the damper 24 may be closed or partly so, for control of the fire on the grate, and secondary air then admitted by way of the damper 49. 35 By supplying such a large amount of fuel at each filling of the stove, the stove will function for a long period of time without further attention. The specific passage of secondary air will now be set forth.

30 Under normal operation the secondary air supply from the ash pit by way of the damper 24 is sufficient, but in cold weather when a hotter fire is required, additional secondary air may be admitted into the secondary air chamber 38 by way of the damper 49.

Secondary air is drawn upwardly through the openings 26 and 26' and the groove 30 of the tile members and finally discharging into the chamber 38. From the chamber 38 the air passes through the openings 48 into the combustion chamber above the fuel.

After refueling of the stove there is a period of coking of the fuel, liberating gases, and while these gases have a tendency to flow upwardly to the top of the fuel level, the large amount of fuel retards such passage, but the provision of the pair of channels between the tile members 33-34, as well as the channels in the cast section 39, provides for free passage of gases. The pockets 35, 45 and 46 function to divert gases to the channels of the tile members and cast sections respectively, while the baffle plates 37 and 47 retard a too rapid passage of the gases, as well as prevent fuel from filling up the channels.

It will thus be seen that the secondary air

emitted through the openings 48 will support combustion of the gases above the fuel, in the form of a circular ring of flame with elimination of smoke.

In order that heat may not pass through the flue 50, a baffle plate 51 is provided projecting inwardly over the major portion of the flue opening.

In Figures 11 to 14, I have illustrated an attachment which may be readily incorporated with the stove structure described to increase the heating efficiency.

In this instance the stove 10' is provided with a cast frame 60 suitably secured thereto, of a depth and width to enclose a radiator 61. The radiator is in the form of a hollow shell, the upper end of which is coupled to the flue opening 52 by means of a pipe coupling 63, and the lower end includes an extension 64 for connection with a chimney or the like. The upper part of the frame 60 is perforated as at 65, to permit heated air to pass from the radiator into a room.

While I have shown and described my stove and furnace structure specifically, this is by way of illustration only, and I consider as my own all such modifications in structure as fairly fall within the scope of the appended claims.

I claim:

1. A heating unit comprising an outer shell having a base and a top, the latter having a fuel feed closure, a grate support on the base, a grate supported thereon above the base defining an ashpit, controllable draft means for the ashpit, a plurality of tile members within the shell in abutting relation thereto defining a fire-pot, said tile members being in edgewise abutting relation except at two diametrically opposite points where the tile members are separated, a spacer member

between said separated tile members, baffle plates on the spacer member and at right angles thereto, the tile members adjacent each vertical edge of the spacer member having a laterally extended pocket, a secondary air chamber above the tile members and supported upon the upper edge thereof, said chamber comprising a plurality of interlocked sections, each of which includes an outwardly turned flange for abutting relation with the shell, and each of said sections further having a vertically disposed channel provided with at least one laterally extended pocket, baffle plates in the channel, certain of the channels being in alignment with the spaced tile members, air passageways between the ashpit and the secondary air chamber and said sections defining the chamber having a plurality of air ports adjacent their upper parts.

2. A heating unit comprising an outer shell having a base and top, a grate spaced above the base, tile members within the shell defining a fire-pot, a secondary air chamber in spaced relation to the casing and supported above and by said tile members, said tile members being constructed and arranged to provide a pair of vertical channels having spaced horizontal baffles of a depth less than the channels, each channel having lateral oppositely disposed pockets, said secondary air chamber being provided with a multiplicity of vertically disposed channels, each of said channels having laterally disposed pockets and vertically spaced horizontal baffles, the baffles being of less depth than the channels, the channels of said tile members being aligned with certain of the channels of the secondary air chamber.

WILLIAM F. ALLEN.
